T. CLARKSON.
PRESSURE CONTROLLED VALVE.
APPLICATION FILED SEPT. 4, 1918.

1,367,864.

Patented Feb. 8, 1921.

FIG. 1

UNITED STATES PATENT OFFICE.

THOMAS CLARKSON, OF CHELMSFORD, ENGLAND.

PRESSURE-CONTROLLED VALVE.

1,367,864.

Specification of Letters Patent.

Patented Feb. 8, 1921.

Application filed September 4, 1918. Serial No. 252,621.

To all whom it may concern:

Be it known that I, THOMAS CLARKSON, a subject of the King of England, and residing at Chelmsford, Essex, England, have 5 invented certain new and useful Improvements in Pressure-Controlled Valves, of which the following is a specification.

This invention relates to pressure controlled valves more particularly valves for 10 regulating the flow of steam or other fluid by variations in steam pressure and has for its object to construct a valve of this type which is more especially designed for use in the control of steam to a jet which is employed for inducing draft in a steam generator heated by solid fuel.

According to this invention the valve comprises a rod which can be rotated or oscillated about its axis and also reciprocated, 20 one end of the rod constituting a valve while the other end is adapted to be acted on by steam pressure in opposition to a suitably disposed spring. The oscillating motion which is imparted to the rod or spindle is 25 preferably slow and alternates through a predetermined angle and serves to keep the spindle free in the stuffing boxes through which it passes at either end so that it will be sensitive to the steam pressure which 30 acts on one end. Thus the rod can be moved longitudinally with ease either to seat the valve or lift it off its seat.

The invention may be put into practice in various ways but the accompanying 35 drawings illustrate by way of example a convenient constructed which may be adopted for the purpose of regulating the flow of steam to the jet of a blower or like device employed in conjunction with the furnace of a steam generator the pressure in 40 which acts on the valve. In these drawings,

Figure 1 is a side elevation of the improved pressure controlled valve.

Fig. 2 is a longitudinal sectional elevation 45 on the line 2-2 of Fig. 1.

Fig. 3 is a transverse section on the line 3-3 of Fig. 1.

Like letters indicate like parts throughout the drawings.

50 The valve spindle A is formed as a rod which toward one end A' is of somewhat larger diameter than the main portion of the rod. This part of larger diameter constitutes a plunger and lies in a cylinder B one end of which is in free communication through a passage B' with the gen-

erator. The plunger A' passes through a stuffing box C of suitable construction. At its opposite end the spindle is coned to constitute a valve A² which lies opposite to a 60 seating D formed in the end of a pipe or passage D' through which steam or air on occasion can flow toward the end of the valve A² into a chamber D² in which the valve lies. A suitable outlet D³ for the 65 steam or air is provided through the side wall of this chamber. The end of this chamber through which the spindle enters carries a stuffing box E of convenient type.

The pressure cylinder B in which lies the 70 plunger A' is positioned opposite to the chamber D² in which is the valve seat D and in the same axial line and the spindle A extends between these two parts. The cylinder B is flanged as at B² and fixed by 75 studs B³ between the ends of the arms F of a U-shaped frame while the valve chamber D² is mounted oppositely in the part F' of the frame which joins the arms F the spindle A thus lying between and parallel to 80 the frame arms or members. The casing constituting the valve chamber has a cylindrical external part D⁴ which is screw-threaded and engaged by nuts G G' which lie as shown in Fig. 2 on either side of a 85 hole F² in the frame part F' through which hole the valve casing passes. Thus it is possible to adjust the position of the valve seat D relatively to the valve A² and pressure cylinder B in the axial direction of the 90 spindle A. The valve chamber can be fixed after adjustment by locknuts mounted on the chamber.

At some intermediate point in the length of the U-shaped frame F there is formed 95 an inwardly directed annular or other flange F³ which serves as an abutment for one end of a coiled spring H which lies around the valve spindle A. The other end of this spring bears against a disk J or washer 100 which is carried on a boss A³ formed on the valve spindle conveniently at that place where the spindle is enlarged to form the plunger A'. This washer J is thus carried adjacent to the end of the pressure cylinder 105 B and the action of the spring H tends to lift the valve A² off its seat D and cause the plunger A' to enter the cylinder B. The steam pressure acts in opposition to this spring H and tends to force the valve A² 110 on to its seat D.

Projecting from the above-mentioned boss

2

A³ on the valve spindle is a lever arm K which is connected to suitable mechanism by means of which the spindle A can be oscillated or given a partial rotation to and fro, 5 the mechanism and connections to this lever arm being such as to permit this oscillation to take place constantly without interfering with the movement of the spindle in the axial direction consequent on the action of 10 the steam or the spring H. In order to allow the necessary play between the washer J against which bears one end of the spring H and the spindle A the washer is conveniently coned internally and the part A⁴ of the boss 15 A³ against which the washer lies is also coned or rounded as shown in Fig. 2. This permits the spring to adjust itself. As the arc through which the spindle A is oscillated is preferably small the effect of this movement on the spring is inconsiderable as the spring will merely tend to slightly wind up and unwind.

If desirable and for the purposes of assisting lubrication of the plunger the cylinder 25 B may contain a small quantity of oil or may be filled wholly or partially with oil so arranged that the steam pressure can act through the oil on the plunger A'.

A pressure controlled valve constructed as 30 above described is more particularly designed for use in conjunction with a steam generator which is heated by solid fuel such as coke and mounted on a motor road vehicle. The steam is allowed to pass from 35 the generator to a jet which is disposed in the flue and there serves as an ejector to draw air through the coke furnace and the products of combustion from the furnace to and through the generator. A similar arrangement may be employed to force air into 40 the furnace so as to control the passage of the products of combustion to the flue. In such a construction it is particularly desirable to have the furnace draft regulated in accordance with the demand on the generator and the pressure therein and by means 45 of such a pressure controlled valve as herein described this can be effected. By movement of the valve chamber D² in the direction of its axis as above described the actuation of 50 the valve A² can be adjusted in accordance with the steam pressure and without adjustment of the spring H which acts on the valve.

55 What I claim as my invention and desire to secure by Letters Patent is:—

1. In a pressure controlled valve the combination of a casing having therein a chamber with inlet and outlet passages and a

valve seat formed at the inner end of the inlet passage, a cylinder to which steam under pressure can be admitted, a member one end of which is formed as a valve adapted to engage the seat in the chamber while the other end constitutes a piston which lies and can move in the cylinder so as to be acted on by the steam therein, stuffing boxes in the chamber and cylinder walls through which said member extends, a spring operative to move the member in opposition to the pressure of the steam in the cylinder, and means for rotating the member as set forth.

2. In a pressure controlled valve the combination of a casing having therein a chamber with inlet and outlet passages and a 75 valve seat formed at the inner end of the inlet passage, a cylinder to which steam under pressure can be admitted, a member one end of which is formed as a valve adapted to engage the seat in the chamber while the other end constitutes a piston which lies and can move in the cylinder so as to be acted on by the steam therein, stuffing boxes in the chamber and cylinder walls through which said member extends, a lever mounted on the 85 member and serving as a means by which the member can be rotated, and a spring operative to move the member in opposition to the pressure of the steam in the cylinder as set forth.

3. In a pressure controlled valve the combination of a casing having therein a chamber and at one end thereof an inlet passage with a valve seat formed at the inner end of the passage and opposite thereto an opening through the wall of the casing provided with a stuffing box while an outlet passage leads laterally from the chamber, a cylinder to one end of which steam under pressure can be admitted while the other end is provided with a stuffing box the cylinder being coaxially disposed in relation to the inlet passage and valve seat in the chamber, a rod-like member one end of which passes through the stuffing box into the chamber 105 and is formed as a valve and adapted to engage the seat in the chamber while the other end which passes through the stuffing box into the cylinder constitutes a piston movable in the cylinder by the action thereon of the steam in the cylinder, a spring operative 110 to move the member in opposition to the pressure of the steam in the cylinder, and means for rotating the member as set forth.

In testimony whereof I have signed my 115 name to this specification.

THOMAS CLARKSON.
